UNITED STATES PATENT OFFICE

147,845

DESIGN FOR A BOOKRACK

Morris Fine, New York, N. Y.

Application June 4, 1946, Serial No. 130,391

Term of patent 3½ years

(Cl. D33—1)

To all whom it may concern:

Be it known that I, Morris Fine, a citizen of the United States, residing in New York, county of New York, and State of New York, have invented a new, original, and ornamental Design for Bookrack, of which the following is a specification, reference being had to the accompanying drawing, forming part thereof.

The figure is a perspective view of a bookrack showing my new design.

I claim:

The ornamental design for a bookrack substantially as shown.

MORRIS FINE.
